Des. 236,368
Patented Aug. 19, 1975

236,368

PICTURE HOLDING PENDANT

Kent L. Jacobson, Moraga, Calif., assignor to Tyrrell Jewelers, Inc., Walnut Creek, Calif.

Filed Dec. 21, 1973, Ser. No. 427,078

Term of patent 14 years

Int. Cl. D11—01

U.S. Cl. D45—15

FIG. 1.

FIG. 5.

FIG. 4.

FIG. 3.

FIG. 2.

FIG. 6.

FIG. 1 is a perspective view of a picture holding pendant showing my new design;

FIG. 2 is a front elevational view;

FIG. 3 is a left side elevational view;

FIG. 4 is a rear elevational view;

FIG. 5 is a top plan view; and

FIG. 6 is a bottom plan view.

I claim:

The ornamental design for a picture holding pendant, substantially as shown and described.
